UNITED STATES PATENT OFFICE.

JOHN MUGFORD, OF PUYALLUP, WASHINGTON.

DESIGN FOR A DRIP-PAN.

SPECIFICATION forming part of Design No. 31,556, dated September 26, 1899.

Application filed August 8, 1899. Serial No. 726,594. Term of patent 14 years.

To all whom it may concern:

Be it known that I, JOHN MUGFORD, a citizen of the United States, residing at Puyallup, in the county of Pierce and State of Washington, have invented and produced a certain new and original Design for Drip-Pans; and I do declare the following to be a full, clear, and exact description of the invention, such as will enable others skilled in the art to which it appertains to make and use the same.

The invention relates to a new and original design for a drip-pan for washboilers and tubs; and it consists of a drip-pan of the configuration shown in the accompanying drawings, in which—

Figure 1 is a perspective view of my design, and Fig. 2 is a longitudinal transverse sectional view.

The leading features of the design consist of the body portion 1, having upwardly-extending side pieces 2, from which project wings 3, the upper edges of which are straight and the lower edge of which is inclined, as shown at 4, and is provided with a vertical slot 5, forming a finger 6.

What I claim is—

The design for a drip-pan as herein shown and described.

In testimony whereof I have hereunto set my hand in presence of two subscribing witnesses.

JOHN MUGFORD.

Witnesses:

GEO. W. EDGERTON,
ALBERT BENNETT.
